UNITED STATES PATENT OFFICE.

CHARLES S. CROSSMAN, OF NEW YORK, N. Y.

DESIGN FOR A BADGE.

SPECIFICATION forming part of Design No. 16,513, dated February 9, 1886.

Application filed December 18, 1885. Serial No. 186,095. Term of patent 14 years.

To all whom it may concern:

Be it known that I, CHARLES S. CROSSMAN, of the city, county, and State of New York, have invented and produced a new and original Design for Badges, of which the following is a specification.

The design of this badge is represented in the accompanying drawing.

The outline of the badge is circular with a ring-shaped border, the background of which is dark and divided into five sections, *a b c d e*. In the center of the badge is a representation of a book as if lying upon the letters "X P," and there is a representation of a wreath within the ring-shaped border and around the representation of the book. The edges and divisions

a' b' c' d' e' of the ring-shaped border *A* and the representation of the book being in light colors, in contrast with the dark background in the ring, produce an artistic effect. 20

I claim—

The design for a badge, consisting of a ring having a dark background divided into sections, and a representation of a book resting upon the letters "X P," and a wreath around 25 the book, substantially as shown and described.

Signed by me this 16th day of December, A. D. 1885.

CHARLES S. CROSSMAN.
